UNITED STATES PATENT OFFICE.

EUGENE SIMEONE, OF WEBSTER, MASSACHUSETTS.

TURNING-TOOL.

1,327,410.

Specification of Letters Patent.

Patented Jan. 6, 1920.

Application filed March 24, 1919. Serial No. 284,757.

To all whom it may concern:

Be it known that I, EUGENE SIMEONE, a subject of the King of Italy, residing at Webster, in the county of Worcester and 5 State of Massachusetts, have invented a new and useful Turning-Tool, of which the following is a specification.

This invention relates to a turning tool particularly designed for refinishing the 10 leather-covered top rolls largely used in yarn drawing and similar operations.

This refinishing involves truing up the new leather covering on each side of each section of the roll, and also facing off the 15 leather on the cylindrical surface of each section. These operations have been heretofore commonly performed by using the ordinary types of side and facing lathe tools, involving the insertion, resetting and removal of three different tools in finishing 20 each section of each roll.

It is the object of my invention to provide an improved turning tool capable of use for performing these three necessary 25 operations on a roll without resetting, removal or replacement.

With this general object in view, my invention relates to certain arrangements and combinations of parts hereinafter described 30 and more particularly pointed out in the appended claims.

A preferred form of my invention is shown in the drawings, in which

Figure 1 is a partial plan view of my improved turning tool, positioned for operation 35 on a top roll;

Fig. 2 is a side elevation of the tool;

Fig. 3 is a plan view thereof, and

Fig. 4 is a sectional view taken along the 40 line 4—4 in Fig. 2.

Referring to the drawings, my improved turning tool comprises a shank 10 having a hole 11 (Fig. 4) extending horizontally through the shank near one end thereof, and 45 having an additional hole 12 adjacent the same end of the shank and extending in an upwardly and downwardly inclined direction, this hole preferably being slightly tapered.

Side finishing tools 13 and 14 are secured 50 to the shank 10 by a bolt 15 extending through the side tools and also through the hole 11 in the shank, the bolt being provided with a nut 16. A stop pin 17 extends 55 through a third hole in the shank and en-

gages the lower ends of the side tools to retain them in operative position, downward pressure upon the cutting edges causing the tools to firmly engage the stop pin 17. The upper outer ends of the side tools 13 and 14 are outwardly beveled to provide the cutting edges shown.

A facing tool 18 is inserted in the upwardly inclined hole 12 in the shank 10, the tool preferably having a slightly tapered 65 body portion fitting the hole 12, and having its upper portion outwardly inclined as clearly shown in Fig. 2. A notch 19 is provided to furnish a shoulder against which to drive the tool firmly in place in the hole 12. 70 The end of the tool is rounded off in plan view, and is tapered and recessed as shown in the drawings to provide a cutting edge.

The use of my improved turning tool is clearly indicated in Fig. 1 in which a double 75 top roll R is indicated in dotted lines with the tool set to bring the side tool 13 into operation. After this side of the roll is faced off, the tool carriage can be moved axially to bring the tool 14 into operation on 80 the opposite side of the roll, after which the roll can be finished on its cylindrical surface by the facing tool 18.

While I have described my improved turning tool as particularly adapted for use 85 in facing top rolls for textile machinery, it is also capable of general application.

Having thus described my invention, it will be evident that changes and modifications can be made therein by those skilled 90 in the art without departing from the spirit and scope thereof as set forth in the claims, and I do not wish to be otherwise limited to the details herein disclosed, but what I claim is—

1. A holder for turning tools having, in combination, a shank, and means to secure a plurality of turning tools thereto, said means comprising a fastening device extending transversely through said shank near 100 one end thereof and through a pair of turning tools disposed one on each side thereof, and means on said shank to prevent angular displacement of said tools.

2. A holder for turning tools having in 105 combination a shank, and means to secure a plurality of turning tools thereto, said means being effective to secure a pair of turning tools to the opposite vertical side faces of said shank, one on each side thereof, 110

and said shank having also provision effective to firmly secure a third turning tool at the end of said shank and between the first mentioned tools.

5 3. A holder for turning tools having, in combination, a shank, and means to secure a plurality of turning tools thereto, said means comprising a fastening device effective to secure a pair of turning tools, one on each side of said shank, and means to prevent angular displacement of said tools, said shank having also an opening adjacent said fastening device, disposed at a slight angle to the vertical and in a vertical plane, within 10 which opening a third turning tool may be

inserted with a driving fit and may be thereby firmly secured.

4. A turning tool having, in combination, a shank with an upwardly inclined tapered hole therein, a facing tool having a body portion fitting said tapered hole, and a cutting portion disposed at an angle to said body portion, said tool having a notch at the upper end of the body portion forming a shoulder against which force may be applied to firmly seat said tool in said shank. 25

In testimony whereof I have hereunto affixed my signature.

EUGENE SIMEONE.
